(57) **CLAIM**

The ornamental design for a scissors blade, as shown and described.

DESCRIPTION

FIG. 1 is a perspective view of a scissors blade showing my new design;

FIG. 2 is a side view thereof;

FIG. 3 is an opposite side view thereof;

FIG. 4 is a front view thereof;

FIG. 5 is a rear view thereof;

FIG. 6 is a top plan view thereof;

FIG. 7 is a bottom plan view thereof; and,

FIG. 8 is a cross sectional view taken along the line 8-8 shown in FIG. 2.

The broken lines in FIGS. 1-8 illustrate portions of the scissors blade that form no part of the claimed design.
